UNITED STATES PATENT OFFICE.

WILLIAM B. GREENLEAF, OF PLYMOUTH, MICHIGAN, ASSIGNOR TO THE MARKHAM AIR RIFLE CO., OF PLYMOUTH, MICHIGAN, A CORPORATION OF MICHIGAN.

AIR-GUN.

1,264,177.

Specification of Letters Patent. Patented Apr. 30, 1918.

Application filed February 9, 1918. Serial No. 216,193.

To all whom it may concern:

Be it known that I, WILLIAM B. GREENLEAF, a citizen of the United States of America, residing at Plymouth, in the county of Wayne and State of Michigan, have invented 5 certain new and useful Improvements in Air-Guns, of which the following is a specification, reference being had therein to the accompanying drawings.

10 This invention relates to guns and refers more particularly to air guns or the like of that type in which the power for propelling the projectile is stored by compressing a spring or the like.

15 In guns of the type above mentioned the projecting power of the gun, which is governed by the power stored when the spring is under compression, is somewhat limited by the fact that the work of compressing the 20 spring by reciprocating the lever or the like must not be beyond the strength of the youth operating the gun.

The present invention contemplates a new 25 and improved construction wherein the work of storing the power is distributed throughout both the movements of the lever or other reciprocating member. The invention also resides in the novel construction and mounting of the spring compressing and locking 30 mechanism and in such other features of construction and arrangements and combinations of parts as will more fully herein-after appear.

In the drawings:

35 Figure 1 is a longitudinal section through a gun embodying my invention;

Fig. 2 is a view similar to Fig. 1 showing the gun partly cocked;

Fig. 3 is a view similar to Fig. 1 showing 40 the gun completely cocked;

Fig. 4 is a vertical section on line 4—4 of Fig. 3;

Fig. 5 is a vertical section on line 5—5 of Fig. 3;

45 Fig. 6 is a fragmentary elevational view showing the inner casing.

Describing in detail the particular embodiment of my invention shown in the drawings, A designates the outer casing of 50 the gun, B the gun stock and C the inner or true barrel which guides the shot or other projectile. The gun illustrated in the drawings is of the type in which there is employed a piston or plunger D which is drawn

backward to compress a spring E for storing 55 the power, by means of which the shot or other projectile is thrown from the true barrel. This plunger may be of any desired construction, and in the present instance is provided with a projection D' which telescopes within the true barrel C. The shank F of the plunger is provided at its rear end with a latch member G which when drawn rearwardly slips over and latches with the sear H and remains in this position until 60 released by rocking the trigger H' about its pivot H².

For cocking the gun there is employed a lever I which is first rocked about its pivot I' forward to the position shown in Fig. 2 70 and then returned to its initial position, as shown in Fig. 3. In order to permit of the use of a relatively strong spring without exceeding the strength of the youth cocking the gun, I have provided a novel arrangement wherein the force provided to compress 75 the spring is divided between the forward and rearward movement of the reciprocating member, such as the lever I. In detail the mechanism for accomplishing this purpose is 80 as follows: At the forward end of the lever I there is pivotally connected at J' a pair of links J which near their opposite ends are apertured at J² to receive a cross pin J³ 85 slidably mounted in an elongated slot F' in the shank F. This shank is preferably built up of spaced bars F² and F³ and secured together by suitable securing members such as the rivets F⁴ extending through spacer members F⁵. The forward part of the lever is 90 enlarged, as shown in Fig. 1, and has a bearing portion K to which there is pivotally secured at K' a pair of links K². These links at their rear ends are apertured at M' to receive a cross pin H² which extends through 95 elongated slots M² in the inner casing member N. The latter fits within the enlargement N' of the outer casing and is removably held in position by a locking member N² and screws N³. This cross pin H² also 100 serves as the pivot for the trigger H'. An inverted U-shaped retaining member O fits over the upper end of the trigger and the enlarged portions O' of the links K² and slides back and forth upon movement of the 105 links K² when the lever I is reciprocated. At its lower end the retaining member O has an abutment member O² between which

and an abutment member H^3 on the trigger there extends the usual trigger spring H^4 .

In cocking the gun the parts operate as follows:

Upon grasping the hand gripping portion I^2 the lever I is rocked forwardly about its pivot I' . This will throw the forward end carrying the cross pin J upwardly and rearwardly and, through the action of the cross pin J^3 on the abutment formed at the end of the slot F' , will force the shank F rearwardly, drawing with it the plunger D and partly compressing the spring E between the plunger D and the stationary abutment Q formed at the forward end of the inner casing member N . At the same time the links K^2 will be drawn forward carrying with them the cross pin H^2 , the retaining member O , the trigger and sear member, these parts being moved forward to the position shown in Fig. 2. At this point the latch member G rides over the sear member H , after which the trigger spring H^4 forces the sear upwardly into latched engagement with the member G . The shank of the piston or plunger D is therefore locked to the sear and through the latter to the cross pin H^2 , at the end of the forward movement of the lever. However, only a portion of the work of compressing the spring has been accomplished during this forward movement, the remaining work being done upon the return movement of the lever to its initial position. At the start of the return movement the pin K' is forced upwardly and rearwardly, which action, through the links K^2 and cross pin H^2 , will carry the retaining member O rearwardly with the trigger and sear member. Therefore, as the shank F of the plunger is locked to the sear the plunger will be further drawn rearwardly and complete the compression of the spring E .

It will be noticed that when the lever I is in the position shown in Fig. 2 it is at a favorable angle for leverage, and I preferably utilize only the first portion of the return movement of the lever for completing the compression of the spring, thus allowing an easy return of the lever to its initial position.

Further as the pin K' moves by the line between the pins I' and H^2 , the power of the spring is reversed in its action with relation to the lever I and the latter is locked solidly against the stock, allowing the gun to remain cocked without being held.

To fire the gun the trigger H' is drawn in the usual manner, releasing the sear H from the latch member G and allowing the spring E to force the plunger forward in the usual manner.

The invention, however, is not necessarily limited to storing the power in a compressed spring nor to the use of a lever as a

reciprocating member. Thus in its broader aspects the invention would include a construction wherein a sliding reciprocating member is employed, and various changes in the details of construction and arrangements and combinations of parts can be made within the scope of my invention.

What I claim as my invention is:—

1. In a gun, the combination with a plunger, of a spring against which said plunger is moved, a reciprocating member and means connecting said member with said plunger, whereby movement of said member in one direction will partially compress the spring, and the return movement of said member will complete the compression of said spring. 70

2. In a gun, the combination with a spring, of means for compressing said spring comprising a reciprocating member and a connection between said member and plunger to partially compress said spring upon the forward movement of said member, and to further compress the spring upon the return movement of said member. 85

3. In a gun, the combination with a spring, of a stationary abutment at one end of said spring, a movable abutment at the other end of said spring, a reciprocating member and a connection between said reciprocating member and said movable abutment for moving the latter toward the stationary abutment upon movement of said reciprocating member in each direction. 95

4. In a gun, the combination with a spring, of a stationary abutment, a lever pivoted to said stationary abutment, a plunger member and link connections between said lever and the plunger member, whereby forward movement of the lever will initially compress the spring and the return movement of the lever further compress the spring. 100

5. In a gun, the combination with a spring, of a plunger member and means for moving said plunger member against said spring to place the latter under compression comprising a lever, a link connected to said lever and having a connection with said plunger so as to move the plunger against the spring upon movement of the lever in one direction, and a second link connected to said lever and having a connection with said plunger for moving the plunger to further compress the spring upon movement of the lever in the opposite direction. 110

6. In a gun, the combination with a plunger and a spring, of a sear adapted to lock the plunger against the spring to hold the latter under compression, a reciprocating member for bringing the sear into latching position upon its forward movement, and a connection between said lever and plunger for further compressing the spring after the plunger has been connected to the sear. 125

7. In a gun, the combination with a cas- 130

ing, of a plunger movable therein, a sear slidably mounted in said casing, and a lever having a connection with said plunger and sear for drawing said parts toward each other upon movement of said lever in one direction and for drawing the sear and plunger in the same direction upon the return movement of the lever, and a spring adapted to be compressed by the plunger upon movement of the lever in each direction.

8. In a gun, the combination with a casing, of a plunger having a shank movably mounted therein, a sear and a trigger also movably mounted in said casing, a spring adapted to be compressed upon movement of the plunger in one direction, and a reciprocating member having a plurality of link connections with the plunger shank and the sear, whereby upon movement of the reciprocating member in one direction the sear and plunger are moved in opposite directions but toward each other, while upon the return movement of the reciprocating mem-

ber the sear and plunger are moved together in the same direction.

9. In a gun, the combination with a plunger and a casing having a stationary abutment, of a spring positioned between said abutment and plunger, a lever member having a link connection and a pin slidably mounted in the casing and adapted upon movement of the lever in one direction to draw the plunger toward the abutment, a sear and releasing trigger slidably mounted in the casing, a second link connection between said lever, sear and trigger whereby the sear is advanced toward the plunger into latching engagement therewith upon the first movement of the lever, and the sear returned to its initial position upon return movement of the lever, said sear carrying with it the plunger so as to further compress the spring.

In testimony whereof I affix my signature.

WILLIAM B. GREENLEAF.
